(57) CLAIM

The design for a convertible baby mat, as shown and described.

DESCRIPTION

FIG. 1 is a bottom perspective view of a convertible baby mat, showing my new design;

FIG. 2 is a front perspective view, showing the handles extended from the pockets and the mat converted to a tote; the rear a mirror image thereof;

FIG. 3 is a top perspective view thereof in a partially open position; and,

FIG. 4 is a top perspective view of the convertible baby mat. The broken lines are for environmental purposes only and form no part of the claimed design.
